CLAIM

The ornamental design for a media processing device as shown and described.

DESCRIPTION

FIG. 1 is a first perspective view of a first embodiment of a media processing device;

FIG. 2 is a second perspective view thereof;

FIG. 3 is a rear side view thereof;

FIG. 4 is a front side view thereof;

FIG. 5 is left side elevation view thereof;

FIG. 6 is right side elevation view thereof;

FIG. 7 is a top side view thereof; and

FIG. 8 is a bottom side view thereof.

FIG. 9 is a first perspective view of a second embodiment of a media processing device;

FIG. 10 is a second perspective view thereof;

FIG. 11 is a rear side view thereof;

FIG. 12 is a front side view thereof;

FIG. 13 is left side elevation view thereof;

FIG. 14 is right side elevation view thereof;

FIG. 15 is a top side view thereof; and

FIG. 16 is a bottom side view thereof.

FIG. 17 is a first perspective view of a third embodiment of a media processing device;

FIG. 18 is a second perspective view thereof;

FIG. 19 is a rear side view thereof;

FIG. 20 is a front side view thereof;

FIG. 21 is left side elevation view thereof;

FIG. 22 is right side elevation view thereof;

FIG. 23 is a top side view thereof; and

FIG. 24 is a bottom side view thereof.

FIG. 25 is a first perspective view of a fourth embodiment of a media processing device;

FIG. 26 is a second perspective view thereof;

FIG. 27 is a rear side view thereof;

(Continued)

FIG. 28 is a front side view thereof;
 FIG. 29 is left side elevation view thereof;
 FIG. 30 is right side elevation view thereof;
 FIG. 31 is a top side view thereof; and,
 FIG. 32 is a bottom side view thereof.

The broken lines immediately adjacent to the claim depict the bounds of the claimed design, while all other broken lines are directed to environment. The broken lines form no part of the claimed design.
